UNITED STATES PATENT OFFICE

2,507,902

ELECTRIC WATER HEATER

Frederick Graves, St. Louis, Mo.

Application August 2, 1948, Serial No. 42,098

6 Claims. (Cl. 219—39)

1

This invention relates to water heaters of the type shown in my copending application Serial No. 608,776, now United States Patent No. 2,446,367.

The principal object of the invention is to provide in the main reservoir of the heater, a dead water well which surrounds the lower portion of the enclosed heating unit and insulates the heated water flowing therethrough from the cooler water in said reservoir adjacent to the cold water inlet thereof.

Another object of the invention is to provide for suspending said enclosed heating unit and well and wiring within the reservoir and for their insertion and removal in assembled relation.

The invention consists in the electric water heater and in the parts and combinations and arrangements of parts hereinafter described and claimed.

The accompanying drawing, which forms part of this specification and wherein like symbols refer to like parts wherever they occur, is a central vertical longitudinal section through an electric water heater embodying my invention.

In the accompanying drawing my invention is shown embodied in an electric water heater comprising a closed upright cylindrical reservoir A, having a cold water inlet 1 near the lower end thereof and a closure plate 3 at the top thereof, and a relatively long and narrow central cylindrical electric heating unit B enclosed in said reservoir concentric therewith and spaced from the side, top and bottom thereof. Surrounding the heating unit B concentric therewith and closely adjacent thereto is a cylindrical tube or shell C having a closed lower end 4 spaced below the lower end of said unit and above the bottom of the reservoir A and having an open upper end extending slightly above the upper end of said unit. Thus, the intermediate casing C cooperates with heating unit B to form therebetween a narrow annular conduit or passageway 5 which leads upwardly from the chamber 6 between the vertically spaced bottoms of said casing and said heating unit and opens into the reservoir A at the open upper end of said casing. A central vertical tubular hot water outlet conduit 7 extends upwardly through the heating unit B from the chamber 6 therebelow and through the top cover plate 3 of the reservoir A. By the arrangement described, the water enters the reservoir A through the inlet conduit 1 in the side thereof and fills said reservoir. The water thence flows downwardly through the annular conduit 5 between the heating unit B and the cylind-

2

rical shell C into the chamber 6 in the bottom of the latter and thence flows upwardly through the central outlet conduit 7 to the discharge end thereof.

5 The electric heating unit B comprises a cylindrical casing 8 having top and bottom closure plates 9 and 10, respectively, through which the central outlet tube or conduit 7 extends. The heating element for said unit comprises a ribbon resistance wire 11 that is helically wound around a supporting core 12 of porcelain or other earthenware refractory material located in the casing 8. The core 12 has an external helical groove 13 in which the helically wound resistance wire 11 is seated; and the outlet tube or conduit 7 extends through an axial bore 14 provided therefor in said core. The ends of the resistance wire 11 extend through the ends of the core 12.

Extending through the top of the reservoir A 20 and the heating unit casing 8 is a wiring conduit 15 for one lead 17 of an electric circuit for energizing the resistance coil 11; and extending downwardly through bottom 10 of casing 8 and thence through low end 4 of cylindrical shell C is a similar wiring conduit 15a for the other lead 17a of said circuit.

25 In accordance with the present invention, the above heater is provided with a cylindrical tube or shell having a closed bottom and open upper end. The shell D surrounds the shell C and is spaced from the side and bottom thereof and extends upwardly along with shell C for the greater portion of its length and provides a dead or still water chamber or well 19 which surrounds the entire lower portion of the shell D and opens at its upper end into the interior of said reservoir.

30 The well forming casing D is spaced from casing C by a series of circumferentially spaced 40 radially disposed spacers 22 that span the annular space between said casings and are welded or otherwise rigidly secured thereto. The wiring conduit 15a extends downwardly into the space between the bottoms of the casing C and the sides forming shell D and thence upwardly between said casing and shell and then through the top cover plate of the reservoir A.

45 As shown in the drawing, a suitable relief valve 21 is located on outlet conduit 7 between cover plate 3 of reservoir A and top closure plate 9 of heating unit B.

50 The cylindrical well casing D, the shell C, and heating unit B are suspended from top cover plate of reservoir A by the outlet conduit 7 and wiring conduits 15 and 15a, all of which are se-

cured to said top by means of annular welds 24. Annular welds 27 also secure the wiring conduits 15 and 15a and outlet conduit 7 to the top closure plate 9 and the bottom closure plate 10 of said heating unit. These welds all provide waterproof joints between the parts connected thereby and they also maintain the parts in proper spaced relation.

When the electric heater unit B is turned on and the water is flowing therethrough in the manner hereinbefore described, the refractory core 12 is heated to a high degree by the resistance wire 11 helically coiled therearound and the heat is transmitted through the water tight coil and core enclosing casing 8 to the thin annular stream of water flowing downwardly through the narrow annular conduit 5 between the spaced sides of the heater unit casing 8 and the intermediate casing C into the chamber 6. The water thence flows upwardly from the chamber 6 through the central outlet conduit 7 where it is again heated by the heated refractory coil supporting core 12. Thus, the flowing water is continuously and rapidly heated during its passage through the electric heater. If the water is not in motion, the relief valve 21 in the outlet conduit 7 allows the water to circulate by its own expansion back into the reservoir.

During the operation of the heater, the earthenware refractory core 12 is heated to incandescence by the heating coil 11 and, after the heater is turned off, this extremely hot core continues to give off heat in the form of radiant energy which serves to keep the water in the storage chamber at a fairly high temperature for several hours. If, within this period of time, the heater is again turned on, an initial supply of hot water is provided until the heater again becomes effective to heat the flowing water. The cylindrical shell D provides a well in which there is little, if any, circulation of water. Hence the water therein is at a temperature only slightly below the temperature of the water in the passageway 5, thereby serving to insulate the water in said passageway from the colder water in the cold water inlet area of the reservoir A and thus increasing the efficiency of the heater. The cylindrical well shell D, the intermediate casing C, the heating unit B and the wiring conduits 15 and 15a are all suspended from the top cover plate 3 of the reservoir A and are all adapted for insertion in and removal from said reservoir in assembled relation.

Obviously, the hereinbefore described electric water heater admits of considerable modification without departing from the invention. Therefore, I do not wish to be limited to the precise arrangements shown and described.

What I claim is:

1. An electric water heater comprising a reservoir having an opening at the upper end thereof, a closure for said opening, a tubular casing located in said reservoir and spaced from the side, top, and bottom and connected only to the top thereof, said tubular casing being closed at its lower end and open at its upper end, an electric heating unit located in said tubular casing and spaced therefrom to form a chamber at the closed lower end thereof and a passageway leading from said chamber and opening into said reservoir at said upper end of said casing, a central outlet tube passing through said electric heating unit and opening at its lower end into said chamber and extending exteriorly of the said reservoir at the upper end thereof, and two wiring con-

duits leading upwardly from the upper and lower ends, respectively, of said heating unit through the upper end of said reservoir, said tubular casing, heating unit, wiring conduits, and outlet tube being connected together for unit insertion in and removal from said reservoir through the opening in the upper end thereof.

2. An electric water heater comprising a reservoir having an inlet in the lower portion thereof, a cylindrical well located in said reservoir and spaced from the side and bottom thereof, said cylindrical well being closed at its lower end and open at its upper end, a tubular casing located within said well concentric therewith, said tubular casing being closed at its lower end and open at its upper end, an electric heating unit located in said tubular casing and spaced therefrom to form a chamber at the closed lower end thereof and a passageway leading from said chamber and opening into said reservoir at said upper end of said casing, and a central outlet tube passing through said electric heating unit and opening at its lower end into said chamber and extending exteriorly of said reservoir at the upper end thereof.

3. An electric water heater comprising a reservoir having an inlet adjacent to the lower end thereof, a cylindrical well located in said reservoir and spaced from the side and bottom thereof, said cylindrical well being closed at its lower end and open at its upper end, a tubular casing located within said well and concentric therewith, said tubular casing being closed at its lower end and open at its upper end, an electric heating unit located in said tubular casing and spaced therefrom to form a chamber at the closed lower end thereof and a passageway leading from said chamber and opening into said reservoir at said upper end of said casing, a central outlet tube passing through said electric heating unit and opening at its lower end into said chamber and extending exteriorly of said reservoir at the upper end thereof, and two wiring conduits leading upwardly from the upper and lower ends, respectively, of said heating unit through the upper end of said reservoir, said cylindrical well, tubular casing, heating unit, wiring conduits, and outlet tube being connected together for insertion in and removal from said reservoir through the opening in the upper end thereof.

4. An electric water heater comprising a closed cylindrical reservoir having an opening at the upper end thereof, a closure for said opening, a cylindrical casing located in said reservoir concentric therewith and spaced from the side, top, and bottom and connected only to the top thereof, said cylindrical casing being closed at its lower end and open at its upper end, a cylindrical electric heating unit located in said tube concentric therewith and spaced therefrom to form a chamber at the closed lower end thereof and an annular conduit leading from said chamber and opening into said reservoir at said open upper end of said casing, an outlet tube passing axially through said electric heating unit and opening at its lower end into said chamber and extending exteriorly of the said reservoir at the upper end thereof, and two wiring conduits leading upwardly from the upper and lower ends, respectively, of said heating unit through the upper end of said reservoir, said cylindrical casing, heating unit, wiring conduits, and outlet tube being connected together for unit insertion in and removal from said reservoir through the opening in the upper end thereof.

5. An electric water heater comprising a closed cylindrical reservoir having an inlet in the lower portion thereof, a cylindrical well located in said reservoir and spaced from the side and bottom thereof, said cylindrical well being closed at its lower end and open at its upper end, a cylindrical casing located within said well concentric therewith, said cylindrical casing being closed at its lower end and open at its upper end, a cylindrical electric heating unit located in said tube concentric therewith and spaced therefrom to form a chamber at the closed lower end thereof and an annular conduit leading from said chamber and opening into said reservoir at said open upper end of said casing, and an outlet tube passing axially through said electric heating unit and opening at its lower end into said chamber and extending exteriorly of said reservoir at the upper end thereof.

6. An electric water heater comprising a closed cylindrical reservoir having an inlet adjacent to the lower end thereof, a cylindrical well located in said reservoir and spaced from but not attached to the side and bottom thereof, said cylindrical well being closed at its lower end and open at its upper end, a cylindrical casing located within said well and concentric therewith, said tubular casing being closed at its lower end and open at its upper end, a cylindrical electric heat-

ing unit located in said tube concentric therewith and spaced therefrom to form a chamber at the closed lower end thereof and an annular conduit leading from said chamber and opening into said reservoir at said open upper end of said casing, an outlet tube passing axially through said electric heating unit and opening at its lower end into said chamber and extending exteriorly of said reservoir at the upper end thereof, and two wiring conduits leading upwardly from the upper and lower ends, respectively, of said heating unit through the upper end of said reservoir, said cylindrical well, cylindrical casing, heating unit, wiring conduits, and outlet tube being connected together for insertion in and removal from said reservoir through the opening in the upper end thereof.
